BINDING

Arthur F. Brook, Madison, N. J.

Application November 7, 1942, Serial No. 464,908

4 Claims. (Cl. 281—21)

The invention herein disclosed relates to bindings and particularly to those of the "permanent," as distinguished from the loose-leaf type.

Objects of the invention are to provide a simple, inexpensive, readily manufactured and easily applied form of binding, which can be made of non-metallic materials, such as plastics and which in addition to the foregoing, will be light in weight, unobtrusive in appearance and, if so desired, actually adding an ornamental or decorative effect to the book structure, of which it may form a part.

The foregoing and other desirable objects are attained by novel features of construction, combination and relation of parts, all as hereinafter defined and broadly claimed.

The drawing accompanying and forming part of the following specification illustrates a practical commercial embodiment of the invention and a present preferred method of application. Structure and mode of application however may be modified and changed within the broad scope of the invention, as will be apparent from the following specification and claims.

Fig. 1 is a plan view of a book having the binding incorporated therein.

Fig. 2 is an edge view showing the appearance of the back of the book.

Fig. 3 is an enlarged broken cross-sectional view as on line 3—3 of Fig. 1.

Fig. 4 is a similar view but showing the book in closed condition.

Fig. 5 is a broken plan illustrating the first stage in applying the binding unit, by first passing the end of the coil at one end of the unit through the leaves or layers that are to be bound together.

Fig. 6 is a similar view illustrating the second stage in which the end of the second coil is started through the adjoining perforation in the sheets and indicating the extent to which the intermediate, bar portion of the unit must be momentarily distorted to permit this dual engagement of the end coils in the leaves.

Fig. 7 is a broken cross-sectional view as on line 7—7 of Fig. 6, illustrating the constriction of the inner convolutions necessary to pass the bar portion across the back edge of the bound leaves.

Fig. 8 is a broken plan showing the binder unit fully seated with the bar serving as a lock to retain it in that relation.

Fig. 9 is a perspective view of the binder element alone.

The book shown in the several views consists of a stack of leaves 10, and a one-piece cover 11, having closed, as distinguished from the open slot form of perforations 12.

These layers of material are bound together by one or more binder units, consisting each of a substantially straight length of material 13, of a length to bridge the space between adjacent perforations and having oppositely pitched coils 14, 15, at opposite ends of the same, forming the ring elements.

As shown particularly in Fig. 9, the two coils start away from the same side of the bar portion and their convolutions advance helically away from the opposite ends of the bar and are substantially equal in diameter and coaxial.

Also, the two coils may be of the same number of turns, two complete turns in the illustration, to substantially fill the elongated rectangular form of openings shown.

The ends of the coils may be abruptly angled as indicated at 16, or they may be pointed or beveled as indicated at 17, and in some instances, both the abrupt and the pointed ends may be provided on the same unit.

The units may be made of various materials. A plastic of good elasticity has been found most desirable. This plastic is obtainable in lengths of small diameter circular cross-section, which in the thermoplastic form may be coiled, while heated and then cooled to set the coils and give the structure a permanent springy character.

The intermediate bar portion 13, connecting the ring forming coils, prevents these coils from being directly turned or screwed into place and requires the unusual method of assembling illustrated in Figs. 5, 6, 7 and 8.

As shown in Fig. 5, first the end 16 of one coil is passed through one set of perforations 12, which can be accomplished by inserting the end while the coil is inclined to the back of the sheets. Then the other coil is brought in toward the back as in Fig. 6, and the other end passed through the adjoining perforations, while the second coil 15, is inclined in the opposite relation from coil 14. With both coils thus started, the outer or end convolutions will be stretched to greater diameter as at 18, Fig. 7, and the inner convolutions, directly connected with the bar portion, reduced or constricted to lesser diameter as indicated at 19, this because of the fact that the end coils are passing through the perforations, inward of the back wall 20, of the stack and the inner convolutions at 19, are compressed against and at the outside of the back wall 20. This temporary segregation of the inner bar-attached convolutions from the outer turns permits then a bodily rotation of the entire unit from the position indicated in Figs. 6, 7, to the fully seated position

indicated in Fig. 8. In reaching this final position, the bar 13, as will be clear from Figs. 6 and 7, will first turn inward and around across the back wall 20, and will then, as the inner turns pass through the perforations, be carried up over the top of the stack extending directly across between adjoining perforations, where it then forms an absolute lock, preventing further rotation in that direction, or in fact, in the opposite direction, if attempt is made to turn the device in the unwinding direction. It will be observed however, that one familiar with the method of assembling, may detach the unit by rotating the same backwardly and at the same time, compressing the inner convolutions sufficiently to force the bar portion to rotate at the back of and against the wall 20, in the reverse of the action described in connection with Fig. 7.

When used with a cover as in the case illustrated, the bar element 13, will be confined at all times between one side of the stack and the back portion of the cover, as shown in Figs. 3 and 4.

For books in the small sizes a single binder unit may be employed and in the larger sizes, as many units as may seem desirable may be used. For a medium size book, such as shown in Figs. 1 and 2, three of the units may be employed.

The binding is particularly light and strong for the amount of material employed. The sheet holding, ring forming coils are the strongest parts of the device and the bar serves as a flexible connection between the ring constituting elements. The coils of two or more turns, by closely fitting the perforations, hold the leaves against undesirable shifting. If plastic is used as the resilient binding medium, the strand may be transparent or colored, thus to be either hardly observable or to actually add a decorative note. While soft and pliable enough to readily bend, as for increasing the diameter of the end convolutions and decreasing the diameter of the intermediate convolutions, the material employed should have enough resiliency to spring back and resume the normal coil diameter.

What is claimed is:

1. The method of binding a stack of perforated sheets, which comprises coiling the opposite ends of a straight strand of flexible, resilient material into oppositely pitched coaxial helical coils spaced

a distance apart corresponding to the spacing of the perforations in said sheets, segregating the outer end convolutions of the coils and starting the same through spaced perforations in the stack and then, while contracting the inner, directly connected convolutions to pass across the edge of the stack, simultaneously rotating the two coils through the perforations until the connecting portion between the coils reaches a position overlying the stack between the coil occupied perforations.

2. The method of applying a binding consisting of a substantially straight strand with oppositely pitched coaxially coiled ends to a stack of perforated sheets and which comprises expanding the end convolutions of the coils and entering said ends in spaced perforations in the stack of sheets, while contracting the inner convolutions connected by the straight portion of the strand to pass across the edge of the stack and then substantially simultaneously rotating both the coils until the substantially straight intermediate connecting portion of the strand brings up against the face of the stack.

3. As a new article of manufacture, a binding element consisting of a single strand of flexible resilient material, having oppositely pitched coaxial helical coils at opposite ends of the same, with the ends of said coils terminating substantially within the circular outline of said coils and said coils consisting each of two or more convolutions.

4. As a new article of manufacture, a binding element comprising a substantially straight bar of flexible resilient plastic having opposite end portions coiled away from the same side of the bar in oppositely pitched coaxial helices of the same diameter, each coil being of substantially two complete convolutions with the convolutions in close side-by-side relation, the ends of said coils being free and lying within the circular outline of the coils, said free ends permitting separation of the outer convolutions sufficiently to be entered in adjoining perforations in a stack of sheets to be bound and the plastic being sufficiently flexible and pliable to permit the simultaneous threading of said oppositely pitched coils completely through said perforations until stopped by the bar portion connecting said coils.

ARTHUR F. BROOK.
